UNITED STATES PATENT OFFICE

127,630

DESIGN FOR A CAMERA

Albert Drucker, Chicago, Ill., assignor to Burke & James, Inc., Chicago, Ill., a corporation of Illinois

Application December 13, 1940, Serial No. 97,295

Term of patent 14 years

To all whom it may concern:

Be it known that I, Albert Drucker, a citizen of the United States, residing at Chicago, in the county of Cook, and State of Illinois, have invented a new, original, and ornamental Design for a Camera, for which the following is a specification, reference being had to the accompanying drawing forming a part thereof.

The figure is a perspective view of a camera showing my new design, the opposite side presenting substantially the same appearance as the side shown and the back of the casing being plain.

I claim:

The ornamental design for a camera, as shown and described.

ALBERT DRUCKER.
